(Cl. D13—1)

FIG. 1

The side of the unit which is not shown is substantially like the one that is shown in the drawings.

I claim:

The ornamental design for a dispensing island shelter unit, substantially as shown and described.
